UNITED STATES PATENT OFFICE.

VICTOR S. LUNDELL AND GUSTAF EDWIN ECKBERG, OF JAMESTOWN, NEW YORK.

HINGE FOR CASEMENT-WINDOWS.

1,383,647.

Specification of Letters Patent.

Patented July 5, 1921.

Application filed September 20, 1920. Serial No. 411,431.

To all whom it may concern:

Be it known that we, VICTOR S. LUNDELL and GUSTAF EDWIN ECKBERG, both citizens of the United States, residing at Jamestown, 5 in the county of Chautauqua and State of New York, have invented new and useful Improvements in Hinges for Casement- Windows, of which the following is a specification.

10 This invention relates to casement windows, and has for its chief characteristic the provision of a novel form of hinge or pivot so that when the window is swung to an opened position, the pivot or hinged side of 15 the window is moved an appreciable distance away from the window casing, thus providing sufficient space to gain access to the outside of the window when it is desired to clean the same.

20 Another object of importance resides in the provision of a novel construction of means whereby the window can be locked at any desired angle.

The nature and advantages of the invention will be better understood when the following detail description is read in connection with the accompanying drawings, the invention residing in the construction, combination and arrangement of parts as claimed.

30 In the drawings forming part of this application like numerals of reference indicate similar parts in the several views and wherein:

Figure 1 is a front elevation of the casement window mounted in accordance with our invention.

Fig. 2 is an enlarged view showing the opened position of the window, and the space provided between the hinge side there- 40 of and the window casing.

Fig. 3 is an enlarged horizontal sectional view through the lower hinge or pivot showing the window in an opened position.

Fig. 4 is an enlarged vertical sectional 45 view through the hinge.

Fig. 5 is an enlarged sectional view taken on line 5-5 of Fig. 3.

Fig. 6 is a perspective view of one of the plates secured to top and bottom of the 50 window casing.

Fig. 7 is a similar view of the plate secured to the sash.

Fig. 8 is a detail view of the link connec- 55 tion.

Fig. 9 is a perspective view of the locking lever and cam.

Fig. 10 is an edge elevation thereof.

Fig. 11 is a detail view of the brace with which the cam coöperates for locking the window at different angles. 60

Fig. 12 is an elevation showing the invention associated with the steel casement.

Fig. 13 is a sectional view showing the closed and opened positions of the window. 65

Referring to the drawings in detail, 10 65 indicates generally the window casing, 11 the window sash, which is pivoted at the top and bottom thereof as clearly shown in Fig. 1 so that the window is permitted to swing outwardly from one side of the window casing. The pivot or hinge for the window at the top and bottom is identical in construction, except that the lower pivot or hinge has associated therewith a means for locking the window at any desired angle 70 75 when opened.

Secured to the upper and lower part of the window casing, are elongated plates 12, each of which is provided with a longitudinally disposed slot 13, a straight flange 14 80 along one of its longitudinal edges, and a flange 15 extended across one end of the plate and having an inclined surface or edge 16. Each of these plates is also provided with an opening 17 for the purpose to be 85 hereinafter described. Secured to the upper and lower part of the window sash 11 are plates 18 of a somewhat similar configuration as the plates 12, each plate 18 including flanges 19 extending along the opposed 90 longitudinal edges for a portion of their length, and connected by a flange 20 extended across one end of the plate as shown.

These flanges 19 and 20 are arranged to embrace the adjacent sides of the window sash, 95 while depending from the opposite end of the plate 18 is a flange 21 having an inclined surface or edge 22 to coöperate with the corresponding surface of the plate 12. Each plate 18 is provided with an opening 23 100 similar to the opening 17 of the plate 12, the respective plates of the top and bottom of the window being connected by means of a link 24. The link 24 is provided with pivot lugs 25 projecting from the opposed sides 105 of the links adjacent the ends thereof, and one of these lugs is received by the opening 17 of the plate 12, while the remaining lug is received by the opening 23 of the plate 18.

Carried by each plate 18 is a pivot 26 110 which operates within the slot 13 of the plates 12, so that subsequent to swinging

the window 11 upon these pivots to its opened position, the window together with the pivot may be moved longitudinally of the plates 12 so as to provide a space between 5 the pivot side of the window and the adjacent side of the window casing, to allow one to project the arms therethrough when it is desired to clean the window. The opened and adjusted position of the window 10 is clearly illustrated in Figs. 2 and 3.

For a purpose of locking the window in any desired angle, we employ a lever 28 which projects horizontally through a slot 29 in a plate 30 secured to the lower member of the 15 window sash. This lever is formed with the end portion 32 which operates in a bore in the lower member of the window sash and which depending portion is pivotally connected with a duplex cam element 33 20 which is provided with a central opening to receive the pivot above referred to. The cam is rotatably mounted upon the pivot and actuated through the instrumentality of the lever 28. Also carried by the pivot and 25 fixed with relation to the cam, is a plate 34 provided with opposed ends 35 disposed to align with the slot 13 of the adjacent plate 12 so as to move in the slot when the window is adjusted. The upper ends of the pins are 30 beveled or inclined as at 36 to coöperate with the cam like projection at 37 of the cam to hold the window in a given position. The lever 28 is provided with a loop or 35 finger receiving opening 28' to facilitate the operation of this lever. As shown in Fig. 1 the only part of the mechanism visible is the operating element.

In practice, when the window is in its closed position as shown in Fig. 1, the lever 40 28 is arranged against the window sash as shown. When it is desired to open the window, the window is swung upon its pivots at the top and bottom outwardly and subsequently moved in the position shown in Fig. 45 2, during which time the pivots travel in the slots 13 of the plates 12, thus moving the pivot or hinged side of the window away from the adjacent side of the window casing for the purpose above mentioned. It is of 50 course manifest, that the plate and the pin, and the cam associated with the lever move with the pivot, after the window has been given the desired angularity with respect to the window sill, the lever 28 is moved 55 away from the window sash, during which time the cam is actuated and moved to active association with the beveled pin at 34. This provides an effective means of holding the window fixed relatively to the window casing in its adjusted position. The window 60 is closed by simply reversing the movements of these parts.

In Figs. 11 and 12 we have shown the invention applied to steel window casement 65 and wherein 38 indicates the slotted member

associated with the window casing, and 39 the window. Secured to the window is a strap 40 which is provided with an apertured lug 41 to accommodate the pivot 42 carried by one end of the links 43, the lug 44 70 carried by the opposite end of the link being pivoted as at 46. The strap is also provided with a pivot 47 which operates in the slot 49, so that subsequent to the swinging of the window outwardly to an opened position, the window can be moved longitudinally of the member 38 for the purpose above mentioned. The invention in this form is otherwise the same as that hereinabove described.

While it is believed that from the foregoing description the nature and advantages of the invention will be readily apparent, we desire to have it understood that we do not limit ourselves to what is herein shown and described, and that such changes may be resorted to when desired as fall within the scope of what is claimed.

What we claim is:

1. In a casement window, means for pivotally mounting the window at one side of the window casing, whereby said pivoted sides of the window may be moved away from the adjacent side of the window casing, and means carried by the window for locking the latter in any adjusted position.

2. A hinge comprising a plate adapted to be secured to a fixed member, a second plate adapted to be secured to a movable member, the first mentioned plate having an elongated slot, a pivot carried by the second mentioned plate and movable within said slot, and a link pivotally connected with the respective plate.

3. A hinge comprising a plate adapted to be secured to a fixed member, a second plate adapted to be secured to a movable member, the first mentioned plate having an elongated slot, a pivot carried by the second mentioned plate and movable within said slot, a link pivotally connecting said plates together, and means carried by the pivots for holding said plates fixed relatively in a given position.

4. A hinge comprising a plate adapted to be secured to a fixed member, a second plate adapted to be secured to a movable member, the first mentioned plate having an elongated slot and an opening therein, a pivot secured to the second mentioned plate and movable within said slot, the second mentioned slot having an opening, a link, lugs projecting from the opposite sides of the link adjacent the ends thereof, and received within the respective openings of the respective plates, and means carried by said pivot for holding said plates fixed relatively in an adjusted position.

5. A hinge, a plate adapted to be secured to a fixed member, a second plate adapted

to be secured to a movable member, the first mentioned plate having an elongated slot, a pivot carried by the second mentioned plate and movable within said slot, a link pivotally connecting said plates, means for locking said plates in a certain adjusted position, including a cam journaled on said pivot, stationary pins co-operating with said cam, and means for actuating said cam for 10 the purpose specified.

6. A hinge comprising a plate adapted to be secured to a fixed member, and having an elongated slot, a second plate adapted to be secured to a movable member, a link having 15 its terminals pivotally connected with said plates, a pivot carried by the second mentioned plate and movable within said slot, stationary pins associated with the pivot and movable within the slot, a cam rotatably 20 mounted on said pivot and adapted to co-operate with said pin for holding said plate

fixed relatively in an adjusted position, and a lever pivotally connected with said cam for actuating the latter.

7. A hinge comprising two plates, one 25 adapted to be secured to a fixed member and the other to a movable member, said plates being arranged in superimposed relation, flanges formed on said plate, one of said plates having an elongated slot, a pivot carried by the other plate and movable within 30 said slot, a link having its terminals pivotally connected with the respective plates, and means associated with the plate carried by the movable member and operable to hold 35 said plates fixed relatively in a given position.

In testimony whereof we affix our signatures.

VICTOR S. LUNDELL.
G. EDWIN ECKBERG.
